INVENTOR.
Charles Rysdon.

BY
Geo. P. Kimmel
ATTORNEY.

UNITED STATES PATENT OFFICE.

CHARLES RYSDON, OF SIOUX FALLS, SOUTH DAKOTA.

PAN.

Application filed February 19, 1923. Serial No. 619,973.

To all whom it may concern:

Be it known that I, CHARLES RYSDON, a citizen of the United States, residing at Sioux Falls, in the county of Minnehaha and State of South Dakota, have invented certain new and useful Improvements in Pans, of which the following is a specification.

This invention relates to pans, designed primarily for use in the feeding of pigs, but it is to be understood that a pan in accordance with this invention can be used for any purpose wherein it is found applicable, and the invention has for its object to provide in a manner as hereinafter referred to, a seamless imperforate feeding pan constructed from a single sheet of metallic material, preferably galvanized iron of substantial thickness, and including a corrugated slightly flaring or outwardly sloping body having the upper marginal portion thereof formed with a narrow snugly fitting overlap of the material from which the pan is constructed, thereby reinforcing or stiffening the top of the pan to prevent the bending or damaging thereof under ordinary conditions of use and shipment.

Further objects of the invention are to provide in a manner as hereinafter referred to, a seamless imperforate feeding pan for the purpose set forth which is simple in its construction, strong, durable, efficient in its use, readily set up and inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a perspective view of a seamless imperforate feeding pan in accordance with this invention.

Fig. 2 is a horizontal sectional view thereof.

A feeding pan in accordance with this invention is seamless, as well as imperforate, and is stamped from a sheet of suitable metallic material, preferably galvanized

iron of substantial thickness to provide a pan when set up, with a rigid characteristic throughout.

The pan includes a bottom 1, which is imperforate, as well as seamless, and further includes a body portion 2, which is also seamless, as well as being imperforate. The body portion 2 is integral with the bottom 1 and at its point of joinder with the bottom 1, is rounded as at 3. The body portion is provided with outwardly and inwardly extending corrugations 4, 5, respectively. The corrugations are formed in the body portion 2 throughout and are substantially V-shaped in contour, with the base thereof slightly rounded, and each of the corrugations gradually increase in depth from its lower to its upper end. The corrugations 4, 5, start from the upper terminus of the rounded portion 3 of the body 2. The body portion 2 is slightly flaring or outwardly sloping and by such construction it provides for the nesting of a series of pans when storing or shipping the same.

The body portion 2 is annular in contour, and the bottom 1 circular, and the said bottom 1 is formed with an annular upwardly extending circular rib 6, which is spaced a substantial distance from the rounded lower portion 3 of the body 2.

The upper marginal portion of the body 2 is formed of two plies of the material from which the pan is constructed, whereby the said marginal portion is reinforced so that the top of the pan will be stiffened to prevent the bending or damage thereof under ordinary conditions of use or when shipping. The manner of setting up the reinforced top marginal portion of the body 2, is formed from a narrow snugly fitting overlap 7 of the material from which the pan is constructed. The narrow overlap 7 is of a contour as to conform to the corrugated body 1 and snugly fit the same, and further is arranged on the outer face of the body portion 2 and by the employment of this reinforcing means, the top edge 8 of the body portion 2 is of a double thickness.

The bead 6 stiffens the body 1 and provides the lower face of the bottom 1, with an annular groove 9, which is continuous, and which is adapted to receive the rib 6 of a lower pan when a plurality of pans are nested.

From the foregoing construction as set forth and shown, an unusually durable feed-

ing pan is set up, which is not only seamless, but also imperforate, and further a pan is set up thereby the top thereof is reinforced so that it cannot become damaged under ordinary conditions, and although the preferred construction of pan is that as described and illustrated, yet it is to be understood that changes in the details of construction can be had which will fall within the 10 light of the invention as claimed.

What I claim is:-

1. A pan for feeding pigs comprising upwardly extending continuous seamless slightly flared rigid metallic body portion 15 having integral therewith a seamless bottom, said body portion provided throughout with inwardly and outwardly extending uniform corrugations, and said body portion further having its top marginal part reinforced by a narrow snugly fitting overlap formed from 20 an integral part of the material from which the body of the body portion is constructed thereby providing the body portion with a top edge of double thickness, said overlap 25 arranged against the outer face of said body portion.

2. A pan for feeding pigs comprising an imperforate upwardly extending continuous seamless slightly flared rigid metallic body portion having formed integral therewith an imperforate seamless bottom formed with an upwardly extending continuous circular rib semi-cylindrical in cross section, said body portion provided throughout with alternately disposed inwardly and outwardly 30 extending corrugations and further having its top marginal part reinforced by a narrow snugly fitting overlap of the material from which the body portion is constructed thereby providing the body portion with a top edge of double thickness, said overlap 40 arranged against and conforming in contour to the outer face of said body portion, the corrugations of said body portion being substantially V-shaped in contour and gradually 45 increasing in depth from the lower to the upper end thereof and further starting at a point in close proximity to the lower terminus of the body portion.

In testimony whereof, I affix my signature hereto.

CHARLES RYSDON.
